UNITED STATES PATENT OFFICE.

WILLIAM J. STOOP, OF WHEELING, WEST VIRGINIA.

APPARATUS FOR HANDLING METAL PLATES AND SHEETS.

1,330,099.

Specification of Letters Patent. Patented Feb. 10, 1920.

Application filed February 16, 1918. Serial No. 217,501.

To all whom it may concern:

Be it known that I, WILLIAM J. STOOP, a citizen of the United States of America, and resident of Wheeling, county of Ohio, and State of West Virginia, have invented 5 certain new and useful Improvements in Apparatus for Handling Metal Plates and Sheets, of which the following is a specification.

10 This invention relates broadly to an apparatus for handling metal plates and sheets, and more particularly to improved means for effecting the transfer of plates and sheets from the finishing rolls of a rolling mill to the shears.

15 The primary object of the invention is to provide a conveyer to which the heated plates and sheets which emerge from the finishing rolls of a mill or mills may be delivered and by which such plates or sheets 20 will be transferred to a point in proximity to the shears with their surfaces free from scratches and other injuries to which they are subjected when handled in the heretofore prevailing manner.

25 A further object is to provide mechanism whereby the plates and sheets are automatically deposited in a position wherein they will be automatically picked up by the 30 conveyer and also to provide mechanism for receiving plates and sheets from said conveyer and for conveying such plates and sheets to the shears. And a still further object is to provide mechanical means for 35 promptly performing the work of transferring heavy metal plates and sheets from the finishing rolls to the shears, heretofore accomplished by the laborious work of dragging them along the floor by hand.

40 With these and other important objects in view, the invention resides in the features of construction, arrangement of parts and combinations of mechanical elements which will hereinafter be fully described, reference 45 being had to the accompanying drawings, in which—

Figure 1 is a top plan view of the invention, partially broken, illustrating diagrammatically the preferred relative arrangement of the various mechanisms involved.

50 Fig. 2 is a partial side elevation of the invention;

Fig. 3 is a similar view, enlarged, of the conveyer, partly in broken section;

Fig. 4 is a partial transverse sectional view of the conveyer;

Fig. 5 is a partial top plan view of the same;

Fig. 6 is an enlarged side elevation of a conveyer-chain link;

Fig. 7 is a similar view of a conveyer finger;

Fig. 8 is an enlarged cross sectional view of a conveyer chain;

Fig. 9 is an enlarged side elevation of a fragmentary portion of a chain;

Fig. 10 is an end view of the chain-protecting guard or shield; and—

Fig. 11 is an enlarged transverse sectional elevation of the cooling mechanism.

Referring to said drawings, in which like designating characters distinguish like parts throughout the several views—

A indicates generally a conveyer by means of which plates or sheets are conveyed from a feed-table B to a delivery table C. Said feed table B is located in a position convenient to the finishing rolls so that plates or sheets received from the latter may be readily transferred thereto. As herein shown, 75 said feed table is designed for use in connection with two sets of finishing rolls D and E, being located in front of and intermediate the latter, as shown in Fig. 1, so that sheets may be delivered to opposite ends thereof from the adjacent rolls. Said table is preferably disposed on a level with the floor, as shown in Fig. 2, and comprises three series of rollers b, b' and b'', the series b being located at and adjacent to one end 80 of the table and being positively driven for carrying sheets deposited thereon to the intermediate series b' the rollers of which are dead, or idle. The series b'' at and adjacent to the opposite end of the table are 85 also positively driven, but in reverse direction, for conveying sheets deposited thereon to said intermediate series b'. As is obvious, sheets delivered to said series b'' from either end remain stationary until picked up by 90 the conveyer A in a manner which will hereinafter be described.

Said conveyer A, which has its receiving end located adjacent to the position of the

idle rollers b^2 of the table comprises a plurality of endless chains, designated generally by the numeral 1, disposed in parallel relation and carried by sprocket wheels 2 mounted upon shafts 3 journaled at opposite ends of a suitable supporting frame 4. Each chain is composed of a plurality of links 5 and 6 mounted upon axle-like shafts or pins 7 carried by rollers 8 which travel forward upon trackways 9 mounted upon the top of the frame 4 and return upon trackways 10. The links 5 are preferably of elongated substantially oval plate-like form, as shown in Fig. 6, and the links 6 are of similar form except that each thereof has formed integral therewith and disposed at a right angle thereto a long finger 6^a which, when the chain travels upon its trackway 9, occupies an approximately upright position. The finger-carrying links 6 have a staggered arrangement in the chain, as shown in Figs. 4, 5, 8 and 9, so that the extra weight of the fingers will be properly distributed to prevent any tendency of the chain to over-turn.

To provide for the maintenance of the various chains 1 in such relation that the fingers 6^a thereof will always be located in transversely alined straight rows, shafts 11 are located at suitable intervals, the same connecting the various chains and displacing link-connecting pins of each, as shown in Figs. 4 and 5.

Mounted upon the shaft 3 which lies adjacent to the feed-table B is a disk 12 which is peripherally recessed to provide alternate rounded projections 13 and recesses 14. The periphery of said disk is engaged by a roller 15 carried by one end of a lever 16 which is pivoted intermediate its ends upon a suitable support, as 17. Pivots connected to the opposite end of said lever 16 is one end of a link 18 which has its opposite end pivotally connected to a crank 19 arm 19 carried by a transverse shaft 20 in front of and adjacent to the feed-table B. Fixed upon said shaft 20 is a tilt-table composed of a plurality of parallel arms 21 which are relatively spaced apart to be movable into and out of positions between the various dead rollers b^2 of said feed-table. Said arms 21 are adapted at one limit of their movement to lie horizontally with their rear ends located below the level occupied by plates or sheets deposited upon said rollers b^2 , and at the opposite limit of movement to lie in substantially the inclined position shown in Fig. 3. In swinging from horizontal to inclined position, actuated by the disk 12 through the intermediate mechanism described, the tilt-table elevates a sheet deposited on the series b^2 of rollers to an inclined position and, at the limit of the tilting movement, such sheet slides edgewise from said tilt-table to a position on the con-

veyer A between two transversely alined rows of fingers 6^a, so that it will be lifted by the fingers of the rearmost of said two rows as the same rise over the rearmost sprocket wheels 2 past said tilt-table. The sheet will thence be carried forward by the conveyer and will slide to a position on the delivery table C from the foremost of the rows of fingers between which it has been so carried when the latter assumes an inclined position in passing over the foremost sprocket wheels 2. The rollers of said delivery table are positively driven and serve to convey sheets deposited thereon to a position convenient to the shears F.

As the sheets or plates are carried forward in upright edgewise positions between the fingers of the conveyer, they may be subjected to cooling blasts of air directed upward into contact therewith from ports or nozzles, as 22; provided in a plurality of transversely disposed tubes 23 to which air is conducted in a suitable manner, as from the interior of a fan casing 24 between which and said tubes is a longitudinally disposed conductor casing 25.

The sprocket wheels 2 have in their peripheries oppositely disposed recesses or seats 2^a adapted for having the chain supporting rollers 8 seat therein as they are carried thereover, successive seats being spaced to correspond with the spacing of said rollers. The disks 12 have the peripheral recesses 14 thereof spaced to correspond with the spacing of said seats 2^a of the sprocket wheels 2 so that the tilt-table arms 21 will be accurately timed to elevate to inclined sheet-delivery position as each row of conveyer fingers 6^a arrives in sheet-receiving position.

A depending apron 26 is carried by each of the end arms 21 of the tilt-table, the same being designed as a guard for preventing sheets from being carried onto the idle rollers b^2 of the feed table while said arms 21 are elevated above the latter.

To protect the links of the conveyer chains from injury which would otherwise result from the edges of the sheets sliding forcibly thereagainst from the tilt-table, a curved plate-like guard or shield 27 is suitably supported in position to be engaged by said edges when the sheets slide from said tilt-table.

In practice, plates or sheets from two sets of finishing rolls D and E may be transferred to the adjacent live rollers b or b' of the feed table B, according as one series or the other is most conveniently located. Each sheet is thence carried forward to a stationary position upon the series b^2 of dead rollers. Then, actuated by the disk 12 and the intermediate mechanism, the arms 21 composing the tilt-table will elevate such sheet to an inclined position whence it will

- slide to a position in overlying relation to the next-underlying row of fingers 6^a of the conveyer, by which as they advance said sheet will be elevated to a substantially upright edgewise position. Such position will be maintained by the sheet during the advance of said conveyer until, in passing over the driven end of the latter, it falls forward upon the fingers 6^a of the row next in advance thereof, upon which it rests until a sufficient inclination is assumed to cause it to slide from the last-mentioned fingers. Sliding from said fingers the sheet is deposited upon the rollers of the delivery table 15 C by which it is conveyed to the shears F. As it is carried forward by the conveyer, the sheet may be cooled by blasts of air delivered thereagainst from the underlying nozzles of the cooling mechanism.
- 20 From the foregoing description it will be understood that the plates or sheets are handled automatically from the moment that they are deposited upon the live rollers of the feed table until they reach the shears; 25 and that, not only is the very heavy labor heretofore involved in dragging the plates and sheets from the finishing rolls to the shears wholly eliminated, but such plates and sheets are not subjected to the injurious 30 abrasion which results from such dragging. Furthermore, when the cooling mechanism is employed, the sheets are uniformly cooled while being transported.
- As is obvious, the conveyer may be employed in connection with a single set of 35 finishing rolls, in which case the employment of the long feed table described may be dispensed with; or, a table embodying only the dead roller portion of the feed table B may be employed. Further, the delivery table may be dispensed with and plates or sheets delivered directly to the shears.
- What is claimed is—
- 45 1. A conveyer for plates and sheets, comprising, in combination with a receiving table embodying idle rollers, a tilt-table embodying parallel arms normally disposed between said rollers and movable to an inclined position, a frame having one end located adjacent to said tilt-table, transverse shafts carried at the opposite ends of said frame, a plurality of conveyer chains, wheels for carrying said chains mounted on said shafts, sheet-supporting fingers carried by said chains at spaced intervals, a peripherally recessed member rotatable through the intermediacy of one of said shafts, and means 50 co-operating with said member and having connection with said tilt-table whereby the latter is actuated to move to and from its inclined position for delivering sheets from said receiving table to said chains between said fingers.
- 55 2. A conveyer for plates and sheets, comprising, in combination with a receiving table embodying idle rollers, a tilt-table embodying parallel arms disposed adjacent to said rollers, said table being movable from a position wherein portions of said arms are disposed between and below the upper surfaces of said rollers to inclined position, a frame having one end located adjacent to said tilt-table, transverse shafts carried at the opposite ends of said frame, a plurality of conveyer chains, wheels for carrying said chains mounted on said shafts, sheet-supporting fingers carried by said chains at spaced intervals, said fingers being disposed in transversely alined rows, a peripherally recessed disk mounted upon the frame-carried shaft which is disposed adjacent to the tilt-table, and means interposed between said disk and said tilt-table and co-operating with the former whereby the latter is actuated to move to and from its inclined position for delivering sheets deposited on said receiving table between said rows of fingers.
3. A conveyer for plates and sheets, comprising, in combination with a receiving table embodying idle rollers, a tilt-table embodying parallel arms disposed adjacent to said rollers, said table being movable from a position wherein portions of said arms are disposed between and below the level of the upper surfaces of said rollers to a forwardly inclined position, a frame having one end located adjacent to said tilt-table, transverse shafts carried at the opposite ends of said frame, a plurality of conveyer chains, wheels for carrying said chains mounted on said shafts, sheet-supporting fingers carried by said chains at spaced intervals, said fingers being disposed in transversely alined rows, a peripherally recessed disk mounted upon the frame-carried shaft which is disposed adjacent to the tilt-table, and means including a lever having a portion in engagement with the periphery of said disk and operatively associated with said tilt-table whereby the latter is alternately actuated to assume horizontal and inclined positions for delivering sheets from said receiving table to positions between said rows of fingers.
4. In a conveyer for metal sheets and the like, the combination with table rollers, of rotatable members, a plurality of endless chains carried by said members, said chains embodying fingers which assume substantially upright positions when in advancing sheet-carrying position, the fingers of said chains being disposed in spaced transverse rows, a peripherally notched disk rotatable with one of said members, a tilt-table comprising arms which normally lie between said table rollers, and automatic means for swinging said tilt-table from its normal position for elevating a sheet deposited on said rollers to a position whence it will slide to

a position between adjacent rows of fingers, said means being actuated to operate as each row of fingers approaches a sheet-supporting position and comprising a pivoted lever 5 which has operative connection at one end with said tilt-table and at its opposite end with the periphery of said disk.

In testimony whereof, I affix my signature in presence of two subscribing witnesses.
